UNITED STATES PATENT OFFICE.

LEON A. WOLTERS, OF CHICAGO, ILLINOIS, ASSIGNOR TO THE THORO CORPORATION,
OF CHICAGO, ILLINOIS, A CORPORATION OF DELAWARE.

MEANS FOR ATTACHING DIRECTION-SHEETS TO CANS.

1,343,953.

Specification of Letters Patent. Patented June 22, 1920.

Application filed May 24, 1919. Serial No. 299,525.

To all whom it may concern:

Be it known that I, LEON A. WOLTERS, a citizen of the United States, residing at Chicago, county of Cook, State of Illinois, have invented a certain new and useful Improvement in Means for Attaching Direction-Sheets to Cans, and declare the following to be a full, clear, and exact description of the same, such as will enable others skilled in the art to which it pertains to make and use the same, reference being had to the accompanying drawings, which form a part of this specification.

My invention has for its object to produce a simple and novel means for attaching a sheet or band containing directions or the like to a can or other container, in such a manner as to give to the container an attractive appearance, permit the sheet or band to be readily detached, and avoid marring the appearance of the container in any way when the strip or band is removed therefrom.

The various features of novelty whereby my invention is characterized will herein-after be pointed out with particularity in the claims; but, for a full understanding of my invention and of its object and advantages, reference may be had to the following detailed description taken in connection with the accompanying drawing, wherein:

Figure 1 is a side elevation of a can of the type commonly used for containing toilet preparations, equipped in accordance with the present invention;

Fig. 2 is a view of the upper end of the can, showing the opposite side from that appearing in Fig. 1; and

Fig. 3 is a top plan view of the can, a part being broken away in order more clearly to show other parts.

Referring to the drawing, 1 represents a cylindrical can having a bead or flange, 2, around the upper end. 3 represents a sheet containing directions or other matter having a length approximately equal to the circumference of the can, so that when it is laid about the can its ends will meet. The sheet is folded upon itself along longitudinal lines, that is lines which extend circumferentially of the can when the sheet is placed in position thereon, so as to give to the folded sheet a width which will not interfere with the harmonious lines of

the package nor with the decorations thereon, but which, if desired, may be decorated so as to blend into the decorative scheme of the package. Thus, for example, the exposed surface of the sheet, when folded 60 and placed around the can, may have the same appearance as the underlying portion of the can, so that the can presents substantially the same appearance regardless of whether or not the sheet is there. 65

For the purpose of fastening the ends of the sheet together and making of it a closed ring, and at the same time holding it in a fixed position lengthwise of the can, I pass over the top of the can a ribbon 70 or the like, 4, one end of which is made to overlie the joint, 5, between the two ends of the sheet while the other end extends downwardly over the sheet at a diametrically opposed point. The two ends of the 75 ribbon are held in place by means of wafers, 6 and 7, respectively; the wafers being larger in diameter than the width of the ribbon so that they may be glued or pasted both to the ribbon and to the outer surface 80 of the sheet on opposite sides of each end of the ribbon. It will be seen that the wafer, 6, in addition to holding one end of the ribbon in place, also serves to fasten the two ends of the sheet together. 85

The end of the ribbon fastened by the wafer 6 may be continued beyond the wafer as indicated at 8 so as to produce an ornamental effect and at the same time provide a tab which may be grasped when it is desired to remove the direction sheet and, by a simple outward pull, destroy the wafer, 6, and thus detach the sheet from the can. 90

In placing the sheet in position, it is preferably drawn snugly against the bead 95 or rib 2 so that it will thereafter be held firmly against movement lengthwise of the can, until intentionally removed.

It will thus be seen that I have produced a simple and novel construction by means 100 of which a direction sheet or other thing that may be folded about a container, may be detachably secured thereto in such a manner that it will be directly before the consumer when he receives the container, which 105 will add ornamentation to the container, and which may be removed from the container in a simple way and without leaving glued surfaces or ragged edges, or pieces of paper attached to the container when the directions 110

are removed. It will also be seen that I have produced a simple and novel means for conveniently attaching a folded sheet to a container without gluing or pasting the 5 several layers together so as to interfere with the convenient opening of the sheet when it is detached.

While I have illustrated and described with particularity only a single preferred 10 form of my invention, I do not desire to be limited to the exact structural details thus illustrated and described; but intend to cover all forms and arrangements which come within the terms employed in the definitions 15 of my invention constituting the appended claims.

I claim:

1. A container having an annular bead adjacent to one end, a sheet folded into the 20 form of a band having a length approximately equal to the circumferential length of said container and wrapped around the container, a ribbon attached at one end to the middle of said band and passing across 25 said end of the container, and a wafer overlying and pasted to the ribbon in the vicinity of the other end, and the meeting ends of said band.
2. A container having an annular bead 30 adjacent to one end, a sheet folded into the form of a band having a length approximately equal to the circumferential length of said container and wrapped around the container, a ribbon attached at one end to 35 the middle of said band and passing across said end of the container, and a wafer overlying and pasted to the ribbon in the vicinity of the other end, and the meeting ends of said band, the latter end of the 40 ribbon projecting beyond said wafer to form a tab to be grasped in order to tear the

wafer and disengage said sheet from the container.

3. A container having an annular bead near one end, a flexible band approximately 45 as long as the circumferential length of the container wrapped around the container in the vicinity of said bead, and a ribbon extending across said end of the container and having its ends attached to said band, one 50 of said ends being attached by a wafer overlying it and pasted to the meeting ends of said band.

4. A container having an annular bead near one end, a flexible band approximately 55 as long as the circumferential length of the container wrapped around the container in the vicinity of said bead, and a ribbon extending across said end of the container and having its ends attached to said band, 60 one of said ends being attached by a wafer overlying it and pasted to the meeting ends of said band, a portion of the latter end of said ribbon projecting beyond said wafer to form a tab tearing the wafer and detach- 65 ing said band from the container.

5. A container having an annular bead adjacent to one end, a sheet folded into the form of a band having a length approximately 70 equal to the circumferential length of said container and wrapped around the container, a ribbon attached at one end to the middle of said band and passing across 75 said end of the container, and a wafer overlying and pasted to the ribbon in the vicinity of the other end, and the meeting ends of said band, the exposed portion of said sheet having the same appearance as the part of the container covered thereby.

In testimony whereof I sign this specification.

LEON A. WOLTERS.
